UNITED STATES PATENT OFFICE.

GEORGE W. WALKER, OF MALDEN, MASSACHUSETTS.

DESIGN FOR A RADIATOR LEG OR LOOP.

SPECIFICATION forming part of Design No. 15,779, dated February 3, 1885.

Application filed December 22, 1884. Term of patent 14 years.

To all whom it may concern:

Be it known that I, GEORGE W. WALKER, a citizen of the United States, residing at Malden, in the county of Middlesex, Commonwealth of Massachusetts, have invented and produced a new and original Design for Radiator Leg or Loop, of which the following is a specification, reference being had to the accompanying drawings, forming part thereof.

10 Figure 1 is a side elevation of my newly-designed radiator leg or loop, and Fig. 2 a central cross-section thereof.

Heretofore radiator loops or legs have been produced which were oval, and also diamond 15 shape in cross-section.

In my newly-designed radiator leg or loop the contiguous members thereof extended above the base *d* are of the peculiar cross-section best represented in Fig. 2, wherein it 20 will be seen that the opposite faces *a a* are *T* shape, while the faces *b b*, as well as the faces directly opposite them, are *A* shape,

the *A* being rather wide spread to form an obtuse-angled face. Were it not for the fins *c*, which constitute a portion of the *T*-shaped 25 faces, the body of the loop or pipe would, in cross-section, show two hexagonal pipes.

My novel design, or the leading feature thereof, is the shape given to the parallel members of the loop when viewed in cross-section 30 and as here represented in Fig. 2.

I claim—

The design for radiator loop or pipe, each half of the leg in cross-section showing two *T*-shaped faces and two *A*-shaped faces, as 35 shown and described.

In testimony whereof I have signed my name to this specification in the presence of two subscribing witnesses.

GEO. W. WALKER
